UNITED STATES PATENT OFFICE.

HARVEY C. NUGENT, OF WINSLOW, WASHINGTON.

VALVE FOR INTERNAL-COMBUSTION ENGINES.

1,192,339.

Specification of Letters Patent. Patented July 25, 1916.

Application filed December 3, 1913. Serial No. 804,391.

To all whom it may concern:

Be it known that I, HARVEY C. NUGENT, a citizen of the United States of America, and a resident of the city of Winslow, in the county of Kitsap and State of Washington, have invented certain new and useful Improvements in Valves for Internal-Combustion Engines, of which the following is a specification.

10 The present invention relates primarily to valves of the rotary type and it has for its main object to provide a structure and mechanism of the above character which will be more efficient in operation.

15 Another aim resides in the provision of a valve which is simple, durable and compact in construction.

20 Further objects will appear as the description progresses and those features of construction, arrangements and combinations of parts on which protection is desired will be succinctly set forth in the appended claims.

25 For a full understanding of my invention, reference is to be had to the following specification and the accompanying drawings in which like characters of reference designate like parts throughout.

30 In the drawings: Figure 1 illustrates the preferred embodiment of my valve as applied to an engine of the internal combustion type. Fig. 2 is a horizontal longitudinal section of the valve. Fig. 3 is a transverse section on line 3-3 of Fig. 1. Fig. 4 is a similar view on line 4-4 of Fig. 1. Fig. 5 is a transverse section through the exhaust ports on line 5-5 of Fig. 1, and Fig. 6 is an end elevation illustrating the supporting means for the manifold member, parts being broken away.

35 The engine 1, illustrated as a four cylinder structure is suitably water jacketed, as at 2, and provided with a head 3 constituting a valve casing joining the four cylinders. The cylinder head, which is provided with a jacket 4, is formed with a longitudinal cylindrical bore 5 from which lead a pair of diametrically opposing intake ports 6 and a similarly arranged number of exhaust ports 7 for each cylinder of the engine. These ports are connected to the respective cylinders by passageways 6' and 7', in the former of which, and adjacent the ports 6, are disposed the igniters 8 disclosed as spark plugs.

40 A valve 9 is disposed in the bore 5 for

rotary movement whereby the pairs of intake and exhaust ports 10 and 11, respectively, provided in the valve may be brought into registering relation with the cylinder 60 head ports. The valve is in the form of a tube having an external flange 9' on one end engaging in the seat 3' of the head and having its opposite end projecting from the head to support a gear 12 which is driven 65 from a working part of the engine to impart rotary action to the valve. Between the cylinders are exteriorly arranged packing rings 13 on the valve for obvious reasons.

70 Within the valve is arranged the intake and exhaust manifolds, the same being formed in a single member 14 having on one end an external flange 15 overlying the flange 9' and engaging the head 3 and having its opposite end extending beyond the valve tube to receive support in the annulus 16 which is braced from the head by webs 17. The manifold member 14 is formed with an annular passage 18 extending nearly the entire length of the member from the flanged end portion, said passage forming the intake manifold which discharges through the ports 19, opposing the intake ports 6, when permitted by the valve ports.

75 The exhaust manifold comprises the central bore 20 which is surrounded by a water space or jacket 21, to insulate the intake manifold, and formed with ports 22 opposing the exhaust ports 7 to receive the exhaust from the latter on passing of the valve ports. Rearwardly directing deflectors 23 are arranged about the ports 22 to perform a dual function, namely, to direct the exhaust gases toward the discharge end of the manifold, and to minimize the back pressure resulting from the gases entering the manifold from opposite sides. The deflectors also gradually taper toward the next inner port to decrease the resistance or back pressure of the discharging gases. A header 24, capping the end of the manifold member opposite from the discharge end, is formed with a water space 21' to communicate with the space 21 and also with a passage 18' which leads to the intake manifold from a gas supply. The water jacket 4 substantially envelops the valve, that portion of the jacket below the valve subjected to the explosive force of the gases in the cylinders being reinforced by longitudinally spaced series of webs or ribs 25. By pro-

viding pairs of spark plugs, one in each intake passage, the resultant pressure on the valve of the explosions will be balanced, and the pressure on the pistons equal from the 5 passageways.

Having thus described my invention, what I claim as new, and desire to secure by Letters Patent of the United States of America, is:—

- 10 1. In a structure of the character described, an exhaust manifold having pairs of opposing exhaust ports leading to a common passageway, and a deflector adjacent each port for directing the exhaust gases.
- 15 2. In a structure of the character described, an exhaust manifold having pairs of opposing exhaust ports leading to a common passageway, and a deflector within said passageway adjacent each port, and adapted 20 to direct the exhaust gases away from the opposing ports.
- 20 3. In a structure of the character described, a casing, an exhaust manifold hav-

ing pairs of opposing exhaust ports leading to a common passageway, means controlling 25 communication of the ports with the casing, and deflector means adjacent each port for directing the exhaust gases from the opposing ports, certain of the deflector means gradually tapering toward the adjacent in- 30 ner port.

4. In a structure of the character de-
scribed, an exhaust manifold having pairs
of opposing exhaust ports leading to a com-
mon passageway, and a deflector within said 35
passageway adjacent each port, and adapted
to direct the exhaust gases in a common di-
rection away from the opposing ports, said
deflectors being tapered toward the next
axially adjacent port. 40

Signed at Seattle, Washington, this 22nd
day of November 1913.

HARVEY C. NUGENT.
